UNITED STATES PATENT OFFICE.

JAY H. HALL, OF CLEVELAND, OHIO, ASSIGNOR TO THE ELECTRIC CONTROLLER AND MANUFACTURING COMPANY, OF CLEVELAND, OHIO, A CORPORATION OF OHIO.

ELECTRIC SWITCH.

1,214,779.

Specification of Letters Patent.

Patented Feb. 6, 1917.

Application filed February 24, 1913. Serial No. 750,191.

To all whom it may concern:

Be it known that I, JAY H. HALL, a citizen of the United States, residing at Cleveland, in the county of Cuyahoga and State 5 of Ohio, have invented new and useful Improvements in Electric Switches, of which the following is a specification.

My invention relates to magnetically operated devices, and particularly to magnetically operated switches.

One of the objects of my invention is to provide a switch having a single magnet or winding which has the characteristic of maintaining its contacts open, not only 15 when its winding is not energized, but also when it is energized above a certain value. The contacts are closed when the current in the winding is below this value.

Another object is to cause the contacts to 20 remain closed as long as the winding is energized.

Figures 1, 2, 3, and 4 of the accompanying drawings show side views of four of the many forms my invention may assume, parts 25 of Figs. 1 and 4 being broken away.

Referring to the drawings, the frame A has mounted therein the winding B. The contacts E and F, which are adapted to be closed by the switch, are normally held open 30 by means of a spring G. It will be readily understood that a pivoted counter weight w can be used in place of the spring G for this purpose, as shown in Fig. 4.

Referring to Fig. 1, the winding B produces a magnetic force between the upper end of the core C and the frame, tending to lift the plunger and the contact E, and also a force between the lower end of the plunger and the portion D of the frame, 40 tending to lower the contact E. The lower portion of the frame is provided with the closed conductors P which dampen out the flux in the portion D of the frame when current first flows through the winding. It 45 is seen, therefore, that when the winding is first energized, the core C will be lifted, due to the attraction between its upper end and the frame, and the contacts E and F will be prevented from closing. Upon a reduction 50 of current in the winding, the core C will drop, and in so doing will compress the spring G, and the magnetic force between the lower end of the core and the portion D

of the frame will close the contacts E and F and hold them closed so long as current 55 flows in the winding B.

The adjustable stop J is provided to limit the upward movement of the core C, in order to change the value of current at which the core C will drop and close the switch 60 contacts. The frame may be provided with projections M and N, of varying dimensions, to properly direct the flux when the core is raised and when the core has dropped to the closed position of the switch.

In Fig. 2, the frame A has the winding B, there being a portion A' of the frame separated from the lower part of the frame by the non-magnetic pieces A². An armature L, carrying the movable contact E, is pivoted 70 to the portion A' of the frame at L'. The armature L is provided with an extension L², which is preferably non-magnetic, and which is adapted to be engaged by a movable lever K, which is pivoted to the frame 75 at K'. The contacts E and F are normally held separated by the spring G. When the winding is energized with a high current, the lever K is pulled down and the armature L is lifted, separating the contacts E 80 and F to a greater extent. When the current in the winding has reduced to a predetermined value, the lever K will be released, and the armature L will drop down, compressing the spring G. The portion L³ of the armature 85 will now be strongly attracted to the frame A, and the switch will remain closed by the magnet and held closed until the current in the magnet is reduced to a very low value.

The lever K is provided with an adjusting 90 screw J, for varying the value at which the lever will be released and the switch contacts closed. The portion of the frame adjacent to L³ may be provided with a closed conductor P, which will dampen out the 95 magnetic flux tending to operate the armature L, and give the lever K time to act in preventing the closure of the switch. Although the closed conductor P at this point is desirable, it is not essential for the proper 100 operation of the switch.

In Fig. 3 the core C is lifted when an excess of current flows through the winding, the pin C' engaging the armature L and preventing the closure of the contacts E and 105 F. The pin C' is preferably of non-mag-

netic material. When the current in the winding is reduced to a predetermined value, the core C is retracted by the spring C², allowing the armature L to compress the 5 spring G and close the contacts E and F. The attraction at the portion of the armature L² to the frame prevents the opening of the contacts until the current in the winding has fallen practically to zero. Different 10 positions of the adjusting screw J, which is mounted on a portion of the frame A³, will cause the switch to close at different values of current. The closed conductor P may be provided in this form, as in the others, for 15 dampening out the flux in this part of the frame, and giving the core C time to act.

In the arrangement shown in all of the figures, if the current is not sufficiently high to prevent the closure of the contacts, the 20 members carrying the contacts will be moved by the magnet to close the contacts. In each of the figures of the drawing the movable magnetic member is moved away from the fixed magnetic member if the current in 25 the winding is above a certain value. This movement increases the reluctance between the said members and prevents the movable member from being drawn toward the other member upon a rush of current.

30 In Fig. 1 I have shown the switch arranged to control the starting of the motor M. When the switch S is closed, current flows through the switch S, the winding B, the resistance R, and the motor M. The 35 current which now flows will cause the core C to rise and prevent the closure of the contacts. When the armature has increased its speed, and thereby increased its counter electro-motive force, the current in the motor circuit will decrease, and when it has 40 reached a proper value for cutting out the resistance R, the core C will drop, and the contacts E and F will be closed. The contacts will then remain closed due to the 45 attraction between the lower end of the core C and the portion D of the switch frame, as before explained. The resistance R is now short circuited, and the motor is connected directly to the source of supply, the winding 50 B remaining in circuit. It is thus seen that the switch contacts will be held closed as long as current is flowing in the motor circuit. To stop the motor, the switch S is 55 opened, whereupon the winding B is de- energized, and the spring G opens the contacts, placing everything in readiness for another operation.

It will be readily understood that a number of switches can be connected to operate 60 consecutively in controlling a series of resistance sections for starting a motor and that the other forms of switches shown in the drawings can be used in such a system.

I claim—

65 1. In an electro-magnetically operated de-

vice, a movable member, a second member separated therefrom, a winding arranged upon energization to generate flux in both members, and means tending to prevent the movable member from moving toward the 70 second member, the flux generated by the winding tending to move the movable member toward the second member but capable of moving the movable member away from the second member when the winding is 75 energized above a predetermined value.

2. In an electromagnetically operated device, a member movable in two directions from its normal position, a second member separated from the movable member by a 80 gap, a winding for producing across the gap a magnetic force for moving said member to a certain position, means for holding the said member away from the said certain position when the winding is not energized, 85 and means acted upon by the flux produced by the winding for causing the movement of the said member still farther away from the said certain position and thereby lengthening the said gap when the current in the 90 winding exceeds a certain value.

3. In an electro-magnetically-operated device, a member movable in opposite directions from its normal position, a winding for producing the actuating force for mov- 95 ing said member to a certain position, a second member moved by said winding, and means by which the second member prevents the movement of the movable member to the said certain position when the current in 100 the winding exceeds a predetermined value.

4. In a switch, a magnetizing winding, a pair of contacts, means normally acting to separate said contacts, a member movable in opposite directions from its normal position 105 and attracted by the winding for closing the contacts, and a second member movable with respect to the first member and moved by the winding to prevent the closure of the contacts when the current in the winding ex- 110 ceeds a certain value.

5. A controlling device for electric circuits, comprising a switch member movable in two directions from its normal position, and an electro-magnet for magnetically 115 holding the same in closed position, means for holding said member in open position when the magnet is not energized, the magnet moving said member to a position of greater opening when the current is relatively high and permits it to be closed when the current falls to a predetermined value.

6. A controlling device for electric circuits comprising a switch member normally held with its contacts separated and movable in two directions from its normal position, and an electro-magnet for magneti- 125 cally holding the contacts in closed position, the said magnet causing the contacts to be more widely separated than normal when 130

the current is relatively high and permits them to close when the current falls to a predetermined value.

7. In an electro-magnetically operated device, a frame of magnetic material, a movable member separated from a portion thereof by an air gap and movable in two directions, a magnetizing winding for producing a flux for moving said member toward said frame portion, and means for temporarily retarding the rise of flux in the air gap when current is admitted to the winding, an excess current in the winding moving said member still farther away from said frame portion during the said retarding of the flux rise.

8. In an electromagnetic switch, switch contacts, a magnetic circuit comprising a

stationary frame and a movable member, an energizing winding therefor, a working gap between the movable member and the stationary frame whereby the movable member may be influenced by current in the winding to close the contacts, and an auxiliary gap in the magnetic circuit whereby when the winding is energized above a predetermined value the working gap is increased and thereby made ineffective to close the contacts.

Signed at Cleveland, Ohio, this 20th day of February, A. D. 1913.

JAY H. HALL.
